UNITED STATES PATENT OFFICE.

WILLIAM ERNST, OF RACINE, WISCONSIN, ASSIGNOR TO HAMILTON BEACH MFG. CO.,
OF RACINE, WISCONSIN, A CORPORATION OF WISCONSIN.

MOTOR BRACKET.

Application filed May 5, 1926. Serial No. 106,979.

This invention relates to improvements in motor brackets, particularly adapted for yieldingly attaching electric motors to sewing machines.

5 It is one of the objects of the present invention to provide a bracket attachment for sewing machines and like devices for holding an electric motor so that the pulley wheel thereof will yieldingly press against 10 the machine hand wheel to frictionally drive the same.

A further object of the invention is to provide a motor bracket so pivoted that the arc of travel thereof is smaller than the 15 radius of the hand wheel adapted to be engaged by the motor pulley wheel, with the result that the force exerted by a spring forces the pulley into continuous yielding contact with the hand wheel.

20 A further object of the invention is to provide a motor bracket of the class described suitable for easy attachment to any of the well known makes of sewing machines.

25 A further object of the invention is to provide a motor bracket of the class described which is of very simple construction, is efficient in operation, is strong and durable, is inexpensive to manufacture, and is 30 well adapted for the purposes described.

With the above and other objects in view the invention relates to the improved motor bracket and its parts and combinations as set forth in the claim and all equivalents 35 thereof.

In the accompanying drawing in which the same reference characters indicate the same parts in all of the views:

40 Fig. 1 is an end view of a sewing machine head equipped with the improved motor bracket and motor carried thereby;

Fig. 2 is a side view thereof; and

Fig. 3 is a sectional view taken on line 3—3 of Fig. 2.

45 In the accompanying drawings it will appear that the head of a sewing machine is designated by the numeral 5 and the machine hand wheel is designated 6. Secured to the side of the head, correctly located with 50 respect to the hand wheel, is a plate or

block member 7 having its inner face curved to correspond with the contour of the head, and the same is held in position by a screw 8.

A U-bracket 9 is secured to the upper inner face portion of a small flat type electric motor 10 and the angular ends or ear portions 11 of the bracket are apertured and engage the upper side portions of the block 7. Screws 12 extend through the apertures of the ears and into the block, and the 60 bracket member is free to pivot on said screws with respect to the block member.

The lower portion of the block member is formed with a centrally positioned, circular recess 13 in which the inner end portion of a 65 spring 14 is seated and secured. The outer end portion of the spring bears against the rear of the motor, as shown in Fig. 1.

Due to the fact that the pivotal arrangement between the members 9 and 7 is such 70 that the arc of travel is less than the radius of the hand wheel, the pressure exerted by the spring will always urge the motor away from the base of the head and yieldingly hold the pulley wheel 15 of the motor in 75 forceful contact with the hand wheel to drive the same.

From the foregoing description it will be evident that the improved motor bracket for sewing machines is of very simple and novel 80 construction, and is well adapted for the purpose set forth.

What is claimed as the invention is:

In combination, a sewing machine head carrying a revoluble hand wheel, a block 85 member secured to the side portion of the head, a U-bracket pivotally secured to the end portions of the block member, a motor secured near its upper portion to said bracket, said motor having a pulley wheel 90 adapted for frictional engagement with said hand wheel, and a spring interposed between the block member and the lower portion of the motor for urging the motor outwardly 95 to yieldingly hold the pulley wheel thereof in engaging position.

In testimony whereof, I affix my signature.

WILLIAM ERNST.
